Roland P. Heinrichs, Lindenhurst, N.Y., assignor to
Uniwave, Inc., Farmingdale, N.Y.

Filed Nov. 10, 1971, Ser. No. 197,566

Term of patent 14 years

Int. Cl. D29—99; D26—03
U.S. Cl. D72—1 E

FIG. 1 is a perspective view of the lantern for indicating machinery status embodying my new design;

FIG. 2 is a side elevational view taken along one of the three banks of lamps, the side elevational view taken along each of said three banks of lamps being substantially identical; and

FIG. 3 is a top plan view thereof.

The post is broken away to indicate indeterminate length.

I claim:

The ornamental design for a lantern for indicating machinery status, shown and described.
